UNITED STATES PATENT OFFICE

2,413,458

TRUCK

David M. Light, Chicago, Ill., assignor to American Steel Foundries, Chicago, Ill., a corporation of New Jersey

Application October 9, 1943, Serial No. 505,620

28 Claims. (Cl. 105—197)

1

My invention relates to railway car trucks and more particularly to a ride control truck incorporating a friction device for dampening oscillations of the truck bolster.

The general object of my invention is to provide a ride control truck wherein normal oscillations of the bolster are damped by a substantially constant amount of friction and unusually great or bouncing oscillations of the bolster, such as may frequently occur under service conditions, are damped by an amount of friction which increases proportionately to the amount of relative movement between the side frame and the bolster.

A specific object of my invention is to design a truck such as above described in which friction shoes are disposed at opposite sides of the bolster in wedge engagement therewith and in frictional engagement with the adjacent columns, each shoe being actuated by a spring compressed between said shoe and an adjacent bolster wall, auxiliary actuating means being provided for each shoe in the form of a spring supported on the side frame and having means projecting through an opening in the bolster wall for cooperation with the main shoe actuating spring. The main spring is precompressed to such an extent that the reactive force thereof during normal oscillation of the bolster is greater than the reactive force of the auxiliary spring. However, during an unusually great or bouncing oscillation of the bolster, the reactive force of the auxiliary spring is greater than that of the main spring.

Still another object of my invention is to design a truck of the above described type wherein the bolster, the side frame columns, and the associated friction devices are formed and arranged to afford a quick wheel change, wherein the bolster is elevated in the bolster opening and removed from the top thereof while the bolster supporting spring group remains in normal assembled relationship with the side frame.

In the drawings,

Figure 1 is a fragmentary side elevation of a railway car truck embodying my invention, one end only of the truck being illustrated inasmuch as it is symmetrical about its transverse center line.

Figure 2 is a fragmentary top plan view of the structure shown in Figure 1 with the side frame illustrated in section through one of the columns.

Figures 3 and 4 are sectional views taken respectively in the longitudinal vertical planes indicated by the lines 3—3 and 4—4 of Figure 2.

2

Figures 5 and 6 are respectively a fragmentary top plan view and a fragmentary side elevation of the bolster.

Figures 7, 8 and 9 illustrate the friction shoe in detail, Figure 7 being a rear elevation taken from the bolster engaging face thereof, Figure 8 being a side elevation, and Figure 9 being a bottom plan view.

Describing my invention in detail, the side frame comprises the tension member 2, the compression member 4, and a column 6 joining said members adjacent each end of the frame to define a central bolster opening 8 and a window opening 10 at each end of the frame. Beneath the bolster opening, the tension member 4 is of box section comprising the bottom chord 12, the top chord 14, the inboard and outboard webs 16 and 18, and the reinforcing rib 20 disposed intermediate said webs and substantially parallel thereto. The top chord 14 is widened and formed with an upstanding flange 22 at each of the inboard and outboard sides thereof, said flanges affording convenient confining means for the bolster supporting springs 24 illustrated in elevation in Figure 3 and diagrammatically in Figures 1, 2 and 4.

Seated as at 26 on the springs 24 is a bolster 28 having at each side thereof a pocket 30 defined by the inboard and outboard walls 32 and 34 (Figure 2) and the transverse web 36 extending therebetween, said web being formed with an arcuate portion 38 for the reception of a portion of the associated friction shoe, as hereinafter discussed. Formed on the bolster within the pocket 30 are the spaced inboard and outboard ledges 40, 40 presenting wedge surfaces 42, 42 (Figure 6) sloping upwardly toward the adjacent column.

A friction shoe 44 is received within each pocket 30, said shoe being of skeletal form, as illustrated in detail in Figures 7 to 9 inclusive and comprising the front or main friction wall 46 frictionally engaged as at 48 with a liner 50 mounted on the column 6. At opposite sides thereof the shoe is provided with the spaced wing members 52, 52 presenting crowned wedge surfaces 54, 54 for complementary wedge engagement at 56 with the surfaces 42, 42, as best seen in Figure 4. The friction shoe also comprises a top wall 58 affording a spring seat as at 60 (Figure 3) for the main actuating spring 62 seated at its lower end on a spring plate 64 mounted within a complementary recess 66 in the bottom wall 68 of the bolster. It may be noted that the friction shoe 44 is formed with a rear wall 70 having a loop 72 received within the arcuately formed por-

tion 38 of the web 36. Defining the rear end of the pocket 30, and aligned with the loop 72 are the openings 74 and 76 formed in the inboard and outboard walls 32 and 34 defining the sides of the pocket. Thus it will be understood that during assembly and disassembly of the truck retaining means, such as pins, may be inserted through the loop 72 and the aligned openings 74 and 76 whereby the friction shoe may be withdrawn from engagement with the column in order to facilitate removal and insertion of the bolster.

An auxiliary shoe actuating spring 78, illustrated in section in Figure 3 and diagrammatically in Figures 1 and 4, is associated with each shoe 44, said spring being seated on the top chord 14 of the tension member and supporting a spring cap 80 having a lug or projection 82 extending through a complementary opening 84 (Figure 3) in the bottom wall of the bolster opening, said projection 82 bearing against the spring plate 64. It will be understood that, as illustrated, the spring 62 is precompressed to such an extent that the reactive force thereof is substantially greater than the reactive force of the auxiliary spring 78. Thus during normal oscillations of the bolster the friction shoe 44 is urged against the column by means of the spring 62 whereby a substantially constant amount of friction is developed during normal oscillations of the bolster. When, however, a relatively great or bouncing oscillation of the bolster occurs, the auxiliary spring 78 is compressed to such an extent that its reactive force becomes greater than the reactive force of the spring 62, and under these conditions, the spring plate 64 is lifted by means of the spring cap 80 from the bottom wall of the bolster, and thus the auxiliary spring 78 is operable to urge the shoe 44 against the column with an increasing pressure proportionate to the downward movement of the bolster.

It will be understood that by means of this novel arrangement normal oscillations of the bolster are resisted by a substantially constant amount of friction developed between the shoes and the columns, and unusually great oscillations of the bolster are resisted by a gradually increasing amount of friction.

It may be noted that the bolster opening 8 comprises a widened upper portion 86, and each side of the bolster 28 is provided with inboard and outboard bolster guide lugs 88, 88, the outboard lugs, as will be clearly apparent from a consideration of Figure 1, being of less depth than the widened upper portion 86 of the bolster opening, whereby the bolster may be elevated therein and removed therefrom along with the friction shoes 44, 44 and the actuating springs 62, 62 during a quick wheel change.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a railway car truck, a side frame comprising a column, a bolster spring-supported from said frame adjacent said column, said bolster comprising spaced top and bottom walls, and friction means comprising a wedge surface on said bolster intermediate said walls, a friction member engaging said surface and a friction surface on said column, a resilient unit compressed between said friction member and one of said walls, and a rigid

member supported from said frame and adapted to project through a complementary opening in said last-mentioned wall for cooperation with one end of said unit to increase the compression thereof under certain operating conditions.

2. In a railway car truck, a side frame comprising spaced columns and an intervening bolster opening, resilient means on said frame in said opening, a bolster supported on said resilient means, a pocket in each side of the bolster with spaced inboard and outboard ledges therein having wedge faces sloping upwardly toward the adjacent column, a friction shoe in each pocket having wing portions in complementary engagement with the associated faces, each shoe being frictionally engaged with the adjacent column, a spring plate in each pocket seated on the bottom wall of the bolster, resilient means bearing against said plates and said shoes, resilient means mounted on said frame, spring caps on said last-mentioned resilient means, having projections extending upwardly through openings in the bottom wall of the bolster and engaged with said plates, said second-mentioned resilient means being precompressed to such an extent that the reactive force thereof is greater than the reactive force of said third-mentioned resilient means during normal oscillations of the bolster, and less than the reactive force of said third-mentioned resilient means during an unusually great oscillation of the bolster.

3. In a railway car truck, a side frame comprising spaced columns and an intervening bolster opening, resilient means on said frame in said opening, a bolster supported on said resilient means, a pocket in each side of the bolster with spaced inboard and outboard ledges therein having wedge faces sloping upwardly toward the adjacent column, a friction shoe in each pocket having spaced wing portions in complementary engagement with the associated faces, each shoe being frictionally engaged with the adjacent column, a spring plate in each pocket seated on the bottom wall of the bolster, resilient means bearing against said plates and said shoes, and resilient means mounted on said frame and cooperating with said plates through openings in said bottom wall, said second-mentioned resilient means being precompressed to such an extent that the reactive force thereof is greater than the reactive force of said third-mentioned resilient means during normal oscillations of the bolster and less than the reactive force of said third-mentioned resilient means during an unusually great oscillation of the bolster.

4. In a railway car truck, a side frame comprising spaced columns and an intervening bolster opening, resilient means on said frame in said opening, a bolster supported on said resilient means, a pocket in each side of the bolster with a wedge surface therein sloping upwardly toward the adjacent column, a friction shoe in each pocket in complementary wedge engagement with the associated surface, each shoe being frictionally engaged with the adjacent column, a spring plate in each pocket seated on the bottom wall of the bolster, resilient means bearing against said plates and said shoes, resilient means mounted on the frame, and spring caps on said last-mentioned resilient means having projections extending upwardly through openings in said bottom wall and abutting respective of said plates, said second-mentioned resilient means being precompressed to such an extent that the reactive force thereof is greater than the reactive force of said third-

mentioned resilient means during normal oscillations of the bolster.

5. In a railway car truck, a side frame comprising spaced columns and an intervening bolster opening, a spring group on said frame in said opening, a bolster supported on said group, a pocket in each side of the bolster with a wedge face therein sloping toward the adjacent column, a friction shoe in each pocket in complementary wedge engagement with the associated face, each shoe being frictionally engaged with the adjacent column, a spring plate in each pocket seated on the bottom wall of the bolster, resilient means bearing against said plates and said shoes, and resilient means mounted on said frame and having means extending upwardly through openings in said bottom wall for abutment with said plates, said first-mentioned resilient means being precompressed to such an extent that the reactive force thereof is greater than the reactive force of said second-mentioned resilient means during normal oscillations of the bolster.

6. In a ride control truck, a side frame comprising spaced columns and an intervening bolster opening, resilient means on said frame in said opening, a bolster supported on said resilient means, a wedge surface on said bolster at each side thereof sloping upwardly toward the adjacent column, a shoe engaging each wedge surface and the associated column, a spring bearing against said shoe and against a spring plate seated on the bottom wall of the bolster, a spring on said frame, and a cap on said last-mentioned spring having a projection extending through an opening in said bottom wall for engagement with said plate, said first-mentioned spring being precompressed to such an extent that the reactive force thereof is greater than the reactive force of said second-mentioned spring during limited oscillations of the bolster on said resilient means.

7. In a ride control truck, a side frame comprising tension and compression members and spaced columns defining therewith a bolster opening, resilient means on said frame in said opening, a bolster supported on said resilient means, a wedge surface on said bolster at each side thereof sloping upwardly toward the adjacent column, a friction shoe engaging each wedge surface and the associated column, and a pair of springs associated with each shoe and arranged in series with a spring plate therebetween, the upper of said springs bearing against the associated shoe and the lower of said springs bearing against the tension member, and an upwardly facing surface on said bolster affording stop means for said plate, said upper spring being precompressed to urge said plate into engagement with said last-mentioned surface during normal oscillations of the bolster.

8. In a railway car truck, a side frame comprising tension and compression members and spaced columns defining therewith a bolster opening, a spring group on said frame in said opening, a bolster supported on said group, a pocket in each side of the bolster with a wedge face therein sloping upwardly toward the adjacent column, friction elements in said pockets in complementary wedge engagement with the associated faces, each element being frictionally engaged with the adjacent column, spring plates seated on the bottom wall of the bolster in respective pockets, resilient means bearing against respective plates and the associated elements, and resilient means seated on said tension member and having spring caps thereon extending upwardly through openings

in said bottom wall for engagement with said plates.

9. In a railway car truck, a side frame comprising spaced columns and an intervening bolster opening, a spring group on said frame in said opening, a bolster supported on said group, a pocket in each side of the bolster with a wedge face therein sloping toward the adjacent column, a friction shoe in each pocket in complementary wedge engagement with the associated face, each shoe being frictionally engaged with the adjacent column, a spring plate in each pocket seated against a wall of the bolster, resilient means bearing against said plates and said shoes, and means mounted on said frame and cooperating with said plates through openings in said bolster wall, said last-mentioned means comprising springs seated against portions of said frame.

10. In a railway car truck, a side frame comprising spaced columns and an intervening bolster opening, a spring group on said frame in said opening, a bolster supported on said group, a pocket in each side of the bolster with a wedge face therein sloping toward the adjacent column, a friction shoe in each pocket in complementary wedge engagement with the associated face, each shoe being frictionally engaged with the adjacent column, a spring plate in each pocket seated against a wall of the bolster, precompressed resilient means bearing against said plates and said shoes, and means mounted on said frame and engageable with said plates through openings in said bolster wall for further compressing said resilient means during unusually great oscillation of the bolster.

11. In a ride control truck, a side frame comprising spaced columns and an intervening bolster opening, resilient means on said frame in said opening, a bolster supported on said resilient means, a wedge surface on said bolster at each side thereof sloping upwardly toward the adjacent column, a shoe engaging each wedge surface and the associated column, a spring bearing against said shoe and against a spring plate seated on the bottom wall of the bolster, a spring on said frame, and a cap on said last-mentioned spring having a projection extending through an opening in said bottom wall for engagement with said plate.

12. In a ride control truck, a side frame comprising spaced columns and an intervening bolster opening, resilient means on said frame in said opening, a bolster supported on said resilient means, wedge means on said bolster at each side thereof sloping upwardly toward the adjacent column, friction shoes engaging said wedge means and the associated columns, and a pair of springs arranged in series between each shoe and the side frame, one of said springs being precompressed and cooperating with abutment means on the bolster to limit expansion thereof.

13. In a railway car truck, a side frame, a spring seat on said frame, resilient means on said seat, a bolster supported by said means, friction devices carried by said bolster at opposite sides thereof, each of said devices being entirely independent of the other and comprising a resilient element and a friction element urged thereby into engagement with a friction surface on said frame for developing a substantially constant amount of friction during normal oscillations of the bolster, and spaced independent means on said frame projecting upwardly from said seat and each being adapted to engage an element of one device for increasing the amount of friction developed by the friction element thereof against

the associated surface during an unusually great oscillation of the bolster.

14. In a railway car truck, a side frame comprising spaced columns and an intervening bolster opening, resilient means on said frame in said opening, a bolster supported on said resilient means, friction means carried by said bolster and cooperating with friction surfaces on said columns for developing a substantially constant amount of friction during normal oscillations of the bolster, and resilient means on said frame cooperating with said friction means for increasing the amount of friction developed thereby during an unusually great oscillation of the bolster.

15. In a railway car truck, a frame member, a bolster resiliently supported therefrom, friction elements in complementary wedge engagement with wedge means on the bolster, said elements being in frictional engagement with friction means on said frame member, precompressed resilient means bearing against said elements and a wall of said bolster, and means mounted on said frame and projecting through openings in said wall said means being operable to further compress said resilient means for increasing the amount of pressure exerted thereby against said elements during an unusually great oscillation of the bolster.

16. In a railway car truck, a side frame comprising spaced columns and an intervening bolster opening, a spring seat on said frame at the bottom of said opening, resilient means on said seat, a bolster supported by said means, friction devices carried by said bolster at opposite sides thereof, each of said devices comprising a friction shoe in wedge engagement with wedge means on the bolster and in frictional engagement with friction means on the adjacent column, and a substantially vertical spring reacting against the bolster and said shoe, and spaced independent means on said frame projecting upwardly from said seat and cooperating with respective springs for increasing the amount of friction developed by said devices during an unusually great oscillation of the bolster.

17. In a railway car truck, a side frame, a spring group on said frame, a bolster supported on said group, a friction device carried by said bolster and cooperating with a friction surface on said frame for developing a constant amount of friction during normal oscillations of the bolster with respect to the frame, and resilient means on said frame cooperating with said device for increasing the amount of friction developed thereby during an unusual oscillation of the bolster.

18. In a railway car truck, a frame member, a bolster resiliently supported therefrom, a friction element in complementary wedge engagement with wedge means on the bolster, said element being in frictional engagement with friction means on said frame member, compressed resilient means reacting against the bolster and said element, and means independent of said friction means cooperating with said resilient means for increasing the amount of pressure exerted thereby against said element during unusual downward movement of the bolster.

19. In a railway car truck, a frame member, a bolster spring-supported therefrom, a friction element in complementary wedge engagement with wedge means on the bolster, said element being in frictional engagement with friction means on said frame member, compressed resilient means reacting against the bolster and said element, and auxiliary resilient means seated at its lower end

5 against the frame member and operatively engaged with said first-mentioned resilient means for increasing the amount of pressure against said element during unusual downward movement of the bolster.

20. In a railway car truck, a side frame comprising a column, a bolster spring-supported from said frame adjacent said column, said bolster comprising spaced top and bottom walls, and friction means comprising a wedge surface on said bolster, a friction member engaging said surface and a friction surface on said column, a resilient member compressed between said friction member and one of said walls, and a rigid member spring-supported from said frame and projecting through a complementary opening in said last-mentioned wall, said rigid member being operatively engaged with one end of said resilient member.

21. In a railway car truck, a supporting member, another member spring-supported therefrom for vertical movement with respect thereto, and friction means comprising a friction shoe and a substantially vertical precompressed spring urging said shoe against converging surfaces on respective members, said spring being supported at one end thereof by a wall of said supported member, and a member mounted on said supporting member and projecting through an opening in said wall for operative engagement with said spring.

22. In a railway car truck, a supporting member, another member spring-supported therefrom, and friction means carried by the supported member comprising a friction shoe and a substantially vertical compressed spring urging said shoe against friction surfaces on respective members, said spring being supported at one end thereof by a wall of said supporting member, and a member resiliently mounted on said supporting member and projecting through an opening in said wall for operative engagement with said spring.

23. In a railway car truck, a side frame with spaced columns, a bolster spring-supported therebetween, and friction means comprising friction elements in wedge engagement with said bolster and in frictional engagement with respective columns, precompressed substantially vertical springs reacting at opposite ends thereof against said bolster and respective elements, and rigid means supported from the frame and adapted to cooperate with the ends of said springs reacting against said bolster for increasing the compression of said springs under certain operating conditions.

24. In a railway car truck, a side frame with spaced columns, a bolster resiliently supported therebetween, and friction means comprising friction elements in complementary wedge engagement with said bolster and in frictional engagement with respective columns, precompressed substantially vertical springs each reacting at opposite ends thereof against said bolster and the associated element, and rigid means resiliently supported from said frame and having operative engagement with the ends of said springs reacting against said bolster for increasing the compression of said springs during an unusually great oscillation of said bolster.

25. In a railway car truck, a side frame comprising a column, a bolster spring-supported from said frame adjacent said column, and friction means comprising a friction shoe having wedge engagement with said bolster and frictional engagement with said column, and a pair of vertical springs arranged in series between said frame and said shoe, one of said springs being precompressed

and cooperating with abutment means on the bolster to limit expansion thereof.

26. In a railway car truck, a side frame comprising a column and a spring seat adjacent thereto, a spring group on said seat, a bolster supported from said group, and friction means comprising a friction shoe having wedge engagement with said bolster and frictional engagement with said column, and a plurality of substantially vertical springs arranged in series between said seat and said shoe for actuation of the latter, the lower of said springs being supported by said seat, and the upper of said springs being precompressed and cooperating with abutment means on the bolster to limit expansion of said upper spring.

27. In a railway car truck, a side frame, a spring group on said frame, a bolster end supported on said group, a friction device carried by said bolster end at each side thereof comprising a spring and friction means urged thereby into engagement with a friction surface on said frame for developing a substantially constant amount

of friction during normal oscillations of the bolster with respect to the frame, and means on said frame engageable with said spring for increasing the amount of pressure exerted thereby against the associated friction means during an unusually great oscillation of said bolster, each of said devices being entirely independent of the other device.

28. In a railway car truck, a frame member, a bolster resiliently supported therefrom, a friction element in complementary wedge engagement with wedge means on the bolster, said element being in frictional engagement with friction means on said frame member, compressed resilient means reacting against the bolster and said element, and means carried by the frame and adapted to engage said resilient means for increasing the amount of pressure exerted thereby against said element during an unusually great downward movement of the bolster.

DAVID M. LIGHT.
